UNITED STATES PATENT OFFICE

UZAL E. COONS, OF CHICAGO, ILLINOIS, ASSIGNOR OF ONE-HALF TO CARL J. KOEPKE,
OF CHICAGO, ILLINOIS

AIR EXTRACTOR FOR PUMPS

Application filed January 19, 1928. Serial No. 247,833.

The invention relates to pumps and more particularly it relates to apparatus for pumping liquids and which apparatus is equipped with a pressure equalizing chamber. Such a pressure equalizing chamber is usually connected with a discharge-valve chamber, which forms a part of the pumping apparatus, and provides a cushion of air adapted to absorb shocks and to equalize pressure during the forward strokes of the pump piston.

In practice it is found that air accumulates in the equalizing chamber, as the pumping process continues, as a result of its being impossible to make the valves air tight. The liquid being pumped usually contains some air disseminated through it which, by reason of the pressure to which it is subjected during the pumping process, is forced out in small bubbles and also adds an accretion to the air contained in the equalizing chamber. These accretions of air, thus added to the initial supply contained in the pressure equalizing chamber, in due course fill the pressure chamber with air. Further pumping causes the air, thus trapped, to gather in the discharge-valve chamber, thereby producing a condition which is commonly spoken of as the pump being "air-bound." The pump is said to be "air-bound" when this accumulation of trapped air in the valve chamber becomes of sufficient volume that the forward stroke of the pump piston no longer forces liquid through the outlet valve of the discharge-valve chamber. Force pumps constructed to discharge liquids will not work against air so that the outlet valve of the valve chamber will not open when the pump piston works against the excess air trapped in the valve chamber. The efficiency of the pump is diminished by the accumulation of only a small quantity of air in the discharge-valve chamber. This efficiency gradually decreases, as the amount of air trapped in the valve chamber increases, until the pump becomes completely "air-bound" and fails to discharge any liquid at all.

The usual method of relieving a pump which has become "air-bound" is to open a

valve or similar means provided for this purpose. The efficiency of the pump is necessarily diminished in the intervals between thus releasing the accumulated air besides requiring close attention by the operator of the pump and it is one of the objects of the invention to provide means which automatically maintains any quantity of air, which has been previously determined as desirable, and automatically releasing any excess accumulations.

Another object is to provide means which is adjustable to vary the amount of air automatically maintained in the pressure-equalizing chamber in accordance with pre-determined estimates of the amount necessary for efficient pumping under different conditions.

Still another object is to generally improve pressure chamber apparatus of the class described.

With the above and other objects in view, the invention consists in the typical details of construction and in the arrangement of parts and combination of parts to be hereinafter more fully described and particularly pointed out in the appended claims.

In describing the invention in detail, reference will be had to the accompanying drawings, wherein like characters of reference denote corresponding parts in the several views and in which

Figure 1 is an elevational view of a pressure chamber connected to a discharge-valve chamber shown in section, and of an auxiliary chamber comprising one embodiment of my invention attached thereto; and

Figure 2 is a sectional view through the auxiliary chamber, drawn to a larger scale.

Referring more particularly to the drawings, the numeral 10 designates the pressure equalizing chamber which is connected with a discharge-valve chamber 11 by means of a conduit 12. An auxiliary chamber 13 is also connected with the discharge-valve chamber 11 by means of a conduit 14. The conduit 14 is shown as threaded into an opening in a cover 15 which forms the top of the chamber 11. The pressure equalizing chamber 10 is fastened to the cover 15 by

any convenient means, preferably tap bolts, not shown.

The auxiliary chamber 13 is directly connected with the chamber 10 by a conduit comprising pipe sections 16 and 17 and L's 18 and 19. For convenience in assembling, the chamber 10 is cast with a neck 20 to which the L 19 is connected by threads interiorly formed on the L and exteriorly on the neck. The chamber 13 has a removable top 21 which is fastened by means of tap bolts 22.

Since the chambers 10 and 13 are directly connected at their top portions and their bottom portions are connected through the valve chamber 11 by the conduits 12 and 14, it is obvious that the pressure of the trapped air will be the same in the two chambers and that the water will be maintained at the same level therein. This arrangement of the main chamber 10 and of the auxiliary chamber 13 is equally adapted for connection with valve chambers in horizontal pump lines and in vertical pump lines.

25 The auxiliary chamber 13 contains a float 23 which is actuated by the liquid contained in the chamber. For this purpose a vent valve is mounted in the wall of the chamber 13. The vent valve comprises among other elements, a plunger 24 which is actuated by the float 23. The plunger 24 is connected with the float 23 by a pivotally mounted arm 25 which has a pivoted connection with an upwardly projecting stem 26. 30 The plunger 24 is reciprocally movable in a member 27 in which the plunger is mounted. The member 27 is mounted in the wall of the chamber 13 and is provided with a bore 28. The bore 28 has a diameter in 35 excess of the diameter of the plunger 24 except at the outer end of the member 27 the diameter is smaller than that of the plunger. The contracted portion of the bore 28 has a tapered connection with the enlarged portion, thereby forming a beveled seat 29 for the plunger 24. The end of the plunger 24 is beveled to fit the seat 29 and form a fluid tight connection therewith when the float 23 is in the position shown.

40 When the liquid to be pumped is at or above the level shown in Figure 2 the vent valve remains closed to the passage of air. Upon the liquid dropping below the level shown, the float will descend and open the 45 valve by unseating the plunger 24, thereby permitting air to pass around the plunger and escape through the contracted portion of the bore 28. If an excess of air is trapped in the chambers 10 and 13, the water will 50 fall below the predetermined elevation shown in Figure 2 and the vent valve will automatically open, thereby permitting air to escape and the water, or other liquid being pumped, to return to the elevation shown.

55 Provision is made for varying the pre-

determined elevation at which the vent valve will open by shortening or lengthening the effective length of the stem 26. This is accomplished by threading or turning the stem 26 into a correspondingly threaded connection in the float 23, such threaded connection comprising an interiorly threaded opening in the neck 30 adapted to receive the lower end of the stem, whereby relative rotation of the float and stem lengthens or shortens 70 the stem as desired.

75 It is obvious that those skilled in the art may vary the details of construction and arrangement of parts without departing from the spirit of my invention, and therefore I 80 do not wish to be limited to such features, except as may be required by the claims.

85 Thus it will be seen that I have provided a device which effectively and automatically operates to extract surplus air from an air equalizing chamber of the class described. While the device is shown as used in connection with a piston pump it is equally adapted for use with pressure equalizing chambers for centrifugal and other types of pumps. 90

I claim:

1. The combination with the discharge chamber of a liquid pump, of a pair of equalizing chambers arranged in horizontal relation, conduits separately connecting the lower portions of the equalizing chambers with the discharge chamber, another conduit connecting the upper ends of the equalizing chambers, and float mechanism positioned in one of the equalizing chambers, said mechanism being operable, by a slight lowering of the normal water level of said equalizing chambers, to open the equalizing chambers to atmosphere pressure. 95

100 2. The combination with the discharge chamber of a liquid pump, of a pair of equalizing chambers arranged in horizontal relation, conduits separately connecting the lower portions of the equalizing chambers with the discharge chamber, another conduit connecting the upper ends of said equalizing chambers, one of the equalizing chambers having a vent connecting said equalizing chambers with the atmosphere, and float mechanism operable to close the vent at a 105 predetermined common liquid level in the equalizing chambers and to open the vent upon a slight lowering of said liquid level.

110 In testimony whereof I affix my signature.
